W. E. GILSON

CHIMNEY

Filed Oct. 14, 1926

UNITED STATES PATENT OFFICE.

WILLIAM E. GILSON, OF ST. LOUIS, MISSOURI.

CHIMNEY.

Application filed October 14, 1926. Serial No. 141,508.

This invention relates to chimneys or stacks, and with regard to certain more specific features to a chimney construction including in a new and improved combination 5 certain features of both masonry and monolithic chimneys.

Among the several objects of the invention may be noted the provision of a positively fire proof chimney which has interlocked and staggered joints which at no place are in alignment or in communication; 10 the provision of a chimney of the class described which has a pleasingly ornamental and weatherproof external surface; the provision of a chimney of the class described in which the fire resisting lining and the ornamental external jacket function as a form for a column of monolithic concrete therebetween, which form needs not be removed 15 upon completion of the stack; and a chimney of the class described which is exceedingly strong and weatherproof, yet economical to build. Other objects will be in part obvious and in part pointed out hereinafter.

20 The invention accordingly comprises the features of construction, and arrangements of parts which will be exemplified in the structure hereinafter described, and the scope of the application of which will be indicated in the following claims.

In the accompanying drawings, in which are illustrated several of various possible embodiments of the invention,

Fig. 1 is a side elevation of one form of the chimney built at the side of a building;

Fig. 2 is an enlarged cross section taken on line 2—2 of Fig. 1;

Fig. 3 is a lower fragmentary vertical section taken on line 3—3 of Fig. 2 and shows 40 certain clean-out or flue arrangements;

Fig. 4 is a view similar to Fig. 3 taken at a lower elevation and shows the connection between the chimney and its foundation;

Fig. 5 is a cross section taken on line 5—5 45 of Fig. 4;

Fig. 6 is a fragmentary longitudinal section illustrating an alternate method of building the chimney; and

Fig. 7 is a cross section taken on line 7—7 50 of Fig. 6.

Similar reference characters indicate corresponding parts throughout the several views of the drawings.

Referring now more particularly to Figs. 55 1 and 2, there is illustrated at numeral 1 a building wall which has a smoke outlet 3 to

which a chimney is to be connected for the purpose of maintaining a draft through said outlet 3 when a source of heat communicates therewith.

In order to accomplish the above result, there is provided a foundation pit 5 which is filled preferably with ordinary gravel or stone concrete 7. During the process of filling this pit, reenforcing rods 9, and rings 65 10 are set and also the lowermost one of a series of external hollow tiles 11. This lowermost external tile is set well down into the concrete pit and filled as the filling of the pit proceeds.

70 The external tiles 11, as stated, are hollow and are preferably of a square cross section or other shape which is not round. They are of the form of tile usually used for purposes of lining flues and the like. For the present purposes these tiles 11 are suitably colored to provide a pleasing external appearance and are given a baked external glaze whereby they are made weatherproof. They may be mottled if desired.

75 After the first tile 11 is set, as above described, its hollow interior is completely filled with concrete and the system of reenforcing rods 9, 10 brought therethrough. The reenforcing system comprises a series 85 of longitudinal rods 9 overlapping at their ends but set substantially in a line, and a plurality of cooperating girth rings 10. These rings 10 may be wired to the longitudinal rods 9. All reinforcements are set 90 as the concrete is about to be poured.

When the lowermost tile 11 has been filled (the reenforcing rods protruding from the top thereof), the next tile 11 is positioned on said lowermost tile and in alignment therewith. The reenforcing system is brought through the second tile and this tile is also filled with gravel concrete. This system of building a structure is continued until a predetermined elevation A—A is reached immediately under the clean-out or flue 3. The above described portion of the structure comprises a foundation.

100 The next tile 11, herein called a connecting tile, is similar to those above described and is similarly placed except that it is provided with an opening 13 aligning with the opening 3. A hollow form or liner 15 is placed in the opening 3 and caused to project into the connecting tile 11 in question. 110 The lower end of the lowermost one of a second series of tile 17 is made to cooperate

and communicate with the hollow form 15. The reenforcing system is brought through the connecting tile 11 in the manner above described and under these conditions this connecting tile is filled to its upper edge with cinder concrete 19 or other material which is adapted to expand and contract without breaking under varying temperatures.

16 The internal tile 17 extends substantially one-half of its own length above its respective external tile 11, and the tile 11 under these conditions is (as described) filled in with concrete up to its upper edge. In 15 other words, the internal and external tile members overlap one another approximately one-half of their lengths or at mid points. It is evident that the exact amount of overlap depends upon strength requirements, the 20 primary consideration being that each time a tile is placed in position, that there will be formed between it and the juxtaposed tile a substantial cavity or form adapted to permit building up of a monolithic column of 25 concrete.

Each of the series of tiles 17 comprises a length of flue lining substantially equal in length to the tiles 11.

In contra-distinction to the tiles 11 which 30 are square, the tiles 17 are circular in cross section. They are made of baked fireproof material but need not be glazed and are also of the class of tile used in lining flues.

The construction is continued in the above 35 manner by applying a square external tile 11 on the stack and bringing up the reenforcing system up through this last tile. This puts the upper edge of the tile 11 a half tile length above the upper edge of the 40 tile 17. Cinder concrete may now be filled in to the edge of the tile 17 (elevation B—B). Next, another tile 17 is applied on its respective stack and as the reenforcing system is carried up cinder concrete is filled 45 in up to the elevation C—C. This process of alternately applying square and round tiles whose edges are disaligned, and filling in concrete to the lowermost edge of a given pair of tiles, while carrying up the reenforcing system between them, is continued indefinitely and may be stopped at any point, 50 one of the tiles 17 being the last one to be used. The reenforcing system is cut-off substantially at the upper edge of the last tile 55 11 to be used. Thus an effective chimney is provided. If desired, the last of the series of the tiles 17 may be made of an odd length so that a pleasing appearing head will be had for the chimney. This last tile 17 may 60 be glazed.

In Fig. 1 is illustrated how an external batter 21 may be readily applied to this type of construction where required. The batter is constructed merely by reducing the sizes 65 of the tiles 11 in the external stack, but not

necessarily their length. The tiles composing the reduced continuation of the external stack of tiles are numbered 23 in the drawings. Fig. 2 illustrates how the reenforcing system of rods is proportioned to 70 be effective throughout the length of the chimney, though variable sizes of external square tile 11, 23 are used.

The concrete may be beveled at the batter 21 and at the head 25 of the chimney. 75 It is to be understood that each addition of concrete is to be placed preferably while the concrete beneath is wet, whereby a positively bound and monolithic structure of concrete is formed; and if work is interrupted, 80 whereby a given portion of the concrete does dry, then when work is resumed, the upper surface of the dried portion should be treated in the usual manner pursued in pouring monolithic forms under such conditions. 85 The purpose of using cinder concrete above a level such as A—A is to provide an expandable non-breakable mass. The interstices in cinders give this quality to cinder concrete. Below the level A—A strength is the only 90 requirement (wide temperature variations not being present) and therefore ordinary gravel or stone concrete or its equivalent may be used.

Fig. 1 illustrates how the chimney may be braced to a building wall 1 by means of U-shaped tie members 27. The chimney may be otherwise braced if desired or built in other locations with respect to the structure it serves. The length of the foundation comprising the filled tiles 11 is variable 100 as well as the proportions of the chimney proper, depending upon circumstances.

Figs. 6 and 7 illustrate a modified method for building up the stack above the level A—A or its equivalent, whereby ordinary gravel or stone concrete or the like is used instead of cinder concrete. As illustrated in said Fig. 6, the method of successively building up the inner and outer tiles, setting the reenforcing system and pouring the gravel or stone is analogous to the method used in the Figs. 1 to 3 construction.

Provision for expansion is provided in the Figs. 6 and 7 construction by inserting four hollow open-end pipes or rods 29 into the first external square tile laid down and outside of the first internal round tile. As concrete is poured it takes a position around the rods 29 but does not fill them as it is too coarse. The rods are of a length adapted to reach above the level of the particular tile up to whose upper edge the poured concrete reaches and to reach above the upper edge of the next alternate tile. This gives the 110 Figs. 6 solid line position of the upper ends of rods 29.

While the concrete is yet wet the rods 29 are twisted and drawn upwardly from their solid line positions shown in Fig. 6 until 115

their upper ends stand above the next alternate tile (shown in dotted lines) a distance equal to their last projection above a tile edge. In other words the rods 29 are drawn 5 up half a tile length after each pouring of concrete and are of such lengths in themselves as to always extend well downwardly into a bed of wet concrete. Thus the rods 29 are drawn along and leave cylindrical passages 31 behind them, which passages take 10 up expansion. The rods are hollow so as to permit atmospheric pressure to enter the expansion passages whereby collapse of said passages is prevented while the concrete is 15 wet. Any suitable number of these rods may be used, four being shown in the present embodiment. As the stack is completed these rods are drawn from the last pour of concrete and the upper ends of the passages 31 20 ends are preferably sealed up.

The above described construction, in both its modifications, is especially applicable to residence chimneys where strength with a graceful form is desired. It is well adapted 25 to extending chimneys in use which are too low in view of surrounding buildings. No painting is required nor dangerous overhanging cap.

It is to be understood that while square 30 external tile are preferable because their four corners (filled with concrete) provide a buttressing effect, yet other shapes of tile may be used in the external column.

Fig. 6 illustrates one of the advantages 35 of the invention which is that any given pouring of concrete may readily be reached for tamping purposes because the next successive tile is not yet placed nor in the way. Another advantage is that the internal and external columns have their respective tiles abutted at disaligned points or elevations, 40 yet the tiles are telescoped to provide forms for the concrete, and these forms need not be removed but serve their described purposes.

It is evident from the above, that this 45 chimney construction comprises telescoping successive pairs of members while filling in a monolithic structure therebetween.

In view of the above, it will be seen that 50 the several objects of the invention are achieved and other advantageous results attained.

As many changes could be made in carrying 55 out the above constructions without departing from the scope of the invention, it is intended that all matter contained in the

above description or shown in the accompanying drawings shall be interpreted as 60 illustrative and not in a limiting sense.

I claim:

1. A chimney construction comprising a column of abutted internal tubular members, a column of external abutted tubular members in spaced relationship to said internal members, a monolithic mass of concrete between said members, the abutments between the internal members and the abutments between the external members being disaligned 65 an amount adapted to provide successive 70 forms, whereby said monolithic column of concrete may be built up.

2. A chimney construction comprising a lower portion comprising a column of abutted 75 external tubular members filled with a monolithic column of reenforced material, said material being monolithically connected with a foundation block, and an upper portion comprising a continuation of said external column augmented by a column of abutted internal tubular members in spaced relationship to said external members, the abutments between the external members and the abutments between the internal members being disaligned so that said 80 members overlap at mid-points and a continuation of said reenforced monolithic material between the said external and internal columns, the reenforcement for said material comprising metallic members joining 85 the foundation block and the upper portion, said reenforcement surrounding said abutted internal tubular members.

3. A chimney construction comprising a lower portion comprising a column of 90 abutted external tubular members filled with a monolithic column of reenforced material, said material being monolithically connected with a foundation block, and an upper portion 95 comprising a continuation of said external column augmented by a column of abutted internal tubular members in spaced relationship to said external members, the abutments between the external members and the abutments between the internal members being disaligned so that said members 100 overlap at mid-points and a continuation of 105 said reenforced monolithic material between the said external and internal columns.

In testimony whereof, I have signed my 110 name to this specification this 11th day of October, 1926.

WILLIAM E. GILSON.
